REINFORCEMENT CAGE

Filed May 29, 1930

FIG. 1.

FIG. 2.

FIG. 3.

INVENTOR:

HOWARD H. JENKINS,

By: Orla D. Ringer,
his Atty.

UNITED STATES PATENT OFFICE

HOWARD H. JENKINS, OF LOS ANGELES, CALIFORNIA, ASSIGNOR TO AMERICAN CONCRETE PIPE CO., OF LOS ANGELES, CALIFORNIA

REINFORCEMENT CAGE

Application filed May 29, 1930. Serial No. 456,922.

This invention relates to devices used for reinforcements in concrete pipes and similar hollow structures.

One of the objects of this invention is to provide a structure that can be properly supported during the manufacture of the concrete product by means of portions of this structure.

Another object is to provide a cage designed to eliminate a sagging of portions of the cage during the manufacture of a concrete structure that is to surround the cage in the finished product.

Another object is to provide a cage designed to locate itself properly within a concrete structure and to indicate its position within the finished product.

Another object is to provide a cage designed to facilitate a proper placing of a cage of elliptical form and adapted to be held in proper position against moving during the manufacture of a concrete product.

Other objects will appear from the following description and appended claims as well as from the accompanying drawings, in which—

Fig. 1 is a general cross section through a reenforced concrete pipe, the reinforcement being of the elliptical form, having additional bars longitudinally disposed intertwined with the reinforcement.

Fig. 2 is a general cross section through a reenforced concrete pipe, the reinforcement being of the cylindrical form illustrated in detail in Fig. 3 with extra longitudinally disposed bars for supporting and holding the cage according to this invention in addition to the normal longitudinal reenforcement.

Fig. 3 is a side elevation of a reenforcement cage having additional longitudinally disposed bars for supporting and holding the cage during the manufacture of a concrete structure besides two cylindrical coils and a longitudinally disposed reenforcement.

Fig. 4 is a fragmentary detail longitudinal section of a concrete pipe properly disposed within the form case and held by extra bolts or bars in proper relation to an end-

form-plate or ring with two reenforcement cages.

Fig. 5 is a fragmentary detail longitudinal section of a slightly modified form, the outer cage being wired to the inner cage. 55

Fig. 6 is a fragmentary longitudinal section through two joining pipes.

One of the principal features of this invention involves the elimination of so-called chairs commonly used for supporting and holding a reenforcement cage properly aligned in a form or form-machine during the manufacture of a concrete pipe or similar hollow structure. 60

Furthermore, even with the use of chairs, 65 it is not always possible to avoid a sagging of a reenforcement in a form when laboring under the disadvantageous condition common with respect to a loose longitudinal interengagement within a cage, but, by imparting a longitudinal stress to the cage, a tight longitudinal support and holding is facilitated. 70

To assure this tight longitudinal condition within a cage, the whole cage is prepared 75 and wound in a certain manner.

In the form illustrated in Fig. 3, a distinct inner coil 7 forms the base of the whole cage. Over this coil 7 another reinforcement winding is arranged with the larger portions 8 80 and 8_a passing back and forth longitudinally integrally with the shorter interconnecting pieces 9 and 9_a on opposite ends of the cage. Over the outside of both, the first base coil 7 and the back and forth windings, another 85 coil 10 is wound to complete the cage as far as the cage winding is concerned.

However, extra or additional bars or rods 11 are intertwined or inserted between the windings of the cage. 90

These rods 11 are designed to be firmly and securely tightened and held to the end-plates or flanges 12 of the form in which the cage is placed when a pipe or similar structure is manufactured, such a support or holding being distinctly illustrated in Figs. 4 and 5. 95

The common practice of tightly holding the end flanges in proper position is by means of tie-rods, indicated at 13 in Fig. 4, over the outside of the outer form 14. 104

Though these tie-rods may still be used, depending on the strain to be applied to the form, and also depending on the size of reenforcement that may be used, which in turn depends on the thickness of material in which the reenforcement may or can be embedded, the inserted reenforcement rods 11 are designed and intended to a great extent to take care of the tightening of the flanges, but more particularly to provide the tight longitudinal support required for properly supporting and holding the cage within the form.

From the illustration in Fig. 1 it will be clear that with such additional rods 11, a elliptical cage can, in the first place, be held properly spaced within a form without any difficulty, while with chairs considerable labor would be involved to take care of the differences in the spacing of the cage from the inside of the form, and, secondly, the disposition of the embedded cage in a concrete pipe can always be ascertained with the utmost certainty, to bring the elliptical reenforcement into the desired or required position to withstand the strain that may rest on such a structure when placed in the ground.

The protruding ends of these rods may serve as connections for joining pipes or may be clipped off as it may be required or desired.

From the illustrations in Figs. 4 and 5 it will also be clear that several cages can be as easily properly located and disposed in a form as one cage.

In the form illustrated in Fig. 4, each distinct cage 15 and 16 is separately by its own rods 11 supported and held in the flange 12; while in the form illustrated in Fig. 5, the outer cage 17 is wired to the inner cage 18 by the ties 19, cages tied together in this manner, of course, forming a single strong structure which can be held properly disposed within a form by rods of a suitable strength.

Having thus described my invention, I claim:

1. In a reenforcement cage, in combination with the intertwined cage material, distinct longitudinal rods embodying means adapted to pass through end flanges and to support and hold the cage longitudinally stressed between the end flanges of a form during the manufacture of a product in which the cage is to be embedded.
2. In a reenforcement cage, helical windings, longitudinal windings over said helical windings, a second helical winding over the longitudinal winding, and distinct longitudinal supporting rods firmly disposed with the longitudinal windings between the first and second-named helical windings.
3. In a reenforcement cage, in combination with the cage material, means for holding the cage material centralized within a form between the and with respect to end-flanges

of the form, and means for holding the cage material stressed longitudinally with respect to the end-flanges.

4. In a reenforcement cage, in combination with the cage material, means for holding the cage material spaced in a predetermined position within a form between the and with respect to end-flanges of the form during the manufacture of a structure in which the cage is to be embedded.

5. In a reenforcement cage, in combination with the cage material, means for holding the cage material spaced in a predetermined position within a form between the and with respect to end-flanges of the form during the manufacture of a product in which the cage is to be embedded and being designed to indicate the position of a certain portion of the cage on the outside of the finished product.

In testimony that I claim the foregoing as my invention I have signed my name.

HOWARD H. JENKINS.
